UNITED STATES PATENT OFFICE.

JOHN R. SULLIVAN, OF RIDGEWOOD, NEW JERSEY, ASSIGNOR TO JOHN BOYLE & COMPANY, INCORPORATED, OF NEW YORK, N. Y., A CORPORATION OF NEW YORK.

SEPARABLE FASTENING FOR AWNINGS.

No. 895,122.

Specification of Letters Patent.

Patented Aug. 4, 1908.

Application filed February 24, 1908. Serial No. 417,465.

To all whom it may concern:

Be it known that I, JOHN R. SULLIVAN, a citizen of the United States, residing in Ridgewood, New Jersey, have invented certain new and useful Improvements in Separable Fastenings for Awnings, of which the following is a specification.

This invention aims to provide a new and improved device for fastening upon a wall or 10 similar support the upper edge of an awning.

The device is also applicable to other uses.

The accompanying drawings illustrate an embodiment of the invention applied to the fastening of the upper edge of an awning to 15 the top of a window frame.

Figure 1 is a vertical section through the upper edge of the awning and the adjacent parts. Fig. 2 is a face elevation of the same.

Referring to the embodiment of the invention illustrated, the awning A is fastened by its upper reinforced edge B to the top C of a window frame. For the purpose of fastening the edge of the awning, screw-eyes D or the like are used, passing through devices 20 which are adapted to be passed over the heads of the screw-eyes when the latter are in one position, and to be prevented from passing over such heads when the screw-eyes are turned to another position. Instead of 25 the screw-eyes D, any device having a similarly shaped head capable of being turned may be used.

For passing over the head of the screw-eye, a fastening device is used comprising wire 30 bent to form an elongated eye having two short vertical sides E, an upper long side F, and a lower long side composed of two parts G. The wire is bent outward from the two parts G at points near the middle of the elongated eye, so as to form an extension H, preferably lying in the plane of the elongated eye. The parts constituting the extension H are bent up at their outer ends to form 40 prongs J, which before use stand in the position shown in dotted lines in Fig. 1. These prongs are sharpened at their ends so that they may be forced through the awning and bent over the same to clamp the device upon the awning. The extension H permits the 45 forcing of the prongs through the awning at a point well within the reinforced edge of the latter, while the elongated eye lies beyond 50

the edge of the awning, so that in use there is no rubbing of the screw-eye D against the edge of the awning.

The horizontally elongated eye has two principal points of advantage. It permits the application or removal of the awning by the turning of the screw-eye D to the position shown in dotted lines in Fig. 2, or the holding of the awning fast by turning the screw-eye to the position shown in full lines; and when the screw-eye is turned to the position shown in full lines the horizontally elongated eye allows a certain lateral play of the edge of the awning relatively to the screw-eyes. Furthermore as compared with an eye elongated vertically the illustrated construction has the advantage of having the fastening point as near the edge of the awning as possible, and thus reducing to a minimum the strain upon the means of attachment of the elongated eye to the awning in high winds.

The two parts of the wire constituting the extension H, and the two prongs J bent up therefrom, are separated from each other by a slight distance equal to or slightly greater than the thickness of the head of the screw-eye. This has the advantage that after the elongated eye is slipped over the screw-eye and the latter turned to a vertical position, it may be screwed in quite far, with the portion of it nearest its shank projecting into the space between the two parts of the extension and the prongs, and in this position holds the edge of the awning against lateral movement.

What I claim is:—

1. A device for fastening awnings, comprising a wire bent to form an elongated eye, the wire being bent outward near the middle of one of the sides of the eye to form an extension outward from the eye and in the same plane therewith, the ends of the wire being sharpened to form prongs and bent upward at the end of such extension, in combination with an awning having a reinforced edge about which said prongs are bent to fasten said eye thereto and in a position beyond the edge of the awning.

2. A device for fastening awnings, comprising a wire bent to form a horizontally elongated eye with short vertical sides E, a

long upper side F, and a lower side in two parts G, the wire being bent outward from the ends of the parts G to form an extension H, and the ends of the wire being sharpened and bent upward to form prongs J, the parts of the wire forming the extension H being slightly separated from each other.

In witness whereof, I have hereunto signed my name in the presence of two subscribing witnesses.

JOHN R. SULLIVAN.
